Fig. 1.

UNITED STATES PATENT OFFICE

2,135,952

PICTURE PROJECTING DEVICE

Clarence L. Stephens, New York, N. Y.

Application March 30, 1938, Serial No. 198,949

8 Claims. (Cl. 88—27)

The present invention relates to a portable, manually operated picture projecting device, and, more particularly, to a readily portable, pistol-shaped device capable of being operated by one hand and provided with a trigger to spin a rotatable film carriage for projecting pictures from a film carried by the carriage onto a suitable screen.

It is an object of my invention to provide a picture projecting device that is relatively light in weight, suitably shaped to be held in one hand of an operator during use and which has a single operating member conveniently located for operation by a finger of the hand holding the device. It is another object of the present invention to provide a picture projecting device having a rotatable film carriage adapted to receive a film bearing a plurality of pictures, characters, or the like, and to present the same in proper position for projection, either successively or by chance.

A further object of the present invention is to provide a simple but sturdy and self-contained picture projecting device which may be easily held in one hand of an operator when in use and which is provided with a rotatable film carriage, an electric light bulb and an operating member conveniently located for operation by a finger of the operator's hand in which the device is held which serves, when actuated, to spin the film carriage and energize the light bulb whereby a different picture may be projected each time the operating member is actuated.

Other objects and advantages of the present invention will become apparent from the following description, taken in conjunction with the drawing, in which:

Fig. 1 represents a perspective view of a picture projecting device embodying the present invention;

Fig. 2 depicts a side elevation of the device shown in Fig. 1 with one half of the casing removed to reveal the interior mechanism and with some parts in section; and

Fig. 3 is a vertical sectional view taken on the line 3—3 of Fig. 2 with certain parts omitted for the sake of clarity.

Generally speaking, the present invention provides a picture projecting device which can easily be held in an operator's hand during use without producing fatigue and which can be operated by a trigger mechanism to move a rotatable picture carriage successively from picture to picture or to spin the rotatable carriage to any picture by chance. In a preferred embodiment, the novel

device is self-contained so that it can be used without external connections, but the invention is not restricted to this feature. An operating lever is preferably provided in a convenient position for operation by a finger of the operator's hand in which the device is held, and in one operative movement, the lever produces a cycle of operations including energizing a light source, projecting a picture, extinguishing the light, and framing a different picture for projection. The operation is so simple that even a small child can use the device as a toy with pleasure and entertainment, but, on the other hand, the device is capable of projecting pictures of such clarity and distinctness that it can be widely used for education, instruction and demonstrations in schools, stores, business establishments, etc. Due to the relatively small size and to the simplicity in construction, my new picture projecting devices embodying the principles of the present invention can be manufactured at very reasonable cost.

Broadly stated, my present invention comprises a casing or holder, a light source, a film bearing a plurality of pictures or characters to be projected, a rotatable carriage for supporting the film and for framing a portion thereof in position for projection through a suitable aperture in the casing, and an operating lever for rotating the carriage and energizing the light source so that a different picture is projected each time the lever is operated. The holder or casing may be conveniently shaped to be held in an operator's hand during use, for example, it may take the form of a pistol, a rifle, etc., but it may have any other suitable shape. The light source is preferably an electric light bulb and it has been found satisfactory in practice to include dry cell batteries within the casing to energize the filament when the picture has been framed for projection. The carriage may be journaled on the casing so as to present different portions of the peripheral area of a disc-shaped film in position for projection as it is rotated. Means are provided for moving the carriage either step-by-step or spinning it rapidly about its axis and allowing it to come to rest through frictional losses.

Referring to the drawing, it will be seen that a pistol-type, projecting device is illustrated in which a two-part casing is provided comprising paired sections A and B hinged together at 10 to form, when closed, a hollow pistol-shaped holder. A latch 11 normally retains the sections A and B in closed position. Each section comprises a barrel portion 12, a handle portion 55

13 and a trigger guard 14. The sections A and B may advantageously be die cast of suitable metal or alloy, but they may also be stamped from sheet metal or molded from thermoplastic materials such as artificial resins, etc., as those skilled in the art will readily understand.

10 The barrel portion 12 has an opening 15 at the front end. Preferably an objective lens 16 is adjustably positioned in the opening 15. The objective lens 16 may comprise a tube 17 and lenses 18 positioned adjacent its ends in a manner well understood by those skilled in the art. By making the opening 15 correspond in size and shape to the tube 17, the objective lens 16 may be frictionally held in adjusted position to focus the image of the projected picture on any desired surface. Lugs 19 on one of the sections A or B hold the objective lens 16 in position when the casing is opened.

20 Within the barrel portion 12 in optical alignment with the objective lens 16 is a projection aperture 20 of any desired shape that may be formed, for example, in a partition 21 secured or integral with the barrel portion 12. Further 25 within the barrel portion 12 and likewise in optical alignment with the objective lens 16 and the projection aperture 20 is an electric light bulb 22 removably mounted in a socket 23 secured to the barrel portion 12. Satisfactory results in practice have been obtained by using a bulb having 30 the glass envelope thickened at the end to condense the light rays emitted from the filament, but it will be understood by those skilled in the art that condensers and/or reflectors may be used 35 to concentrate the light in a beam directed toward the projection aperture 20.

A film carriage 24 is rotatably mounted on the holder or casing. The film carriage itself supports a film 25 and is so mounted as to position 40 portions of the film 25 in the beam of light passing from the bulb 22 through the projection aperture 20. The film 25 may be constructed of any suitable materials, and I do not desire to be limited to any particular type. It is only necessary 45 that some material be used on which a picture or character can be formed, brought or produced and which will transmit or reflect rays of light whereby the picture or character thereon can be projected. The film 25 is preferably large 50 enough to bear quite a number of pictures, characters, or the like, for projection, and it has been found satisfactory to make the film in the form of a disc with the pictures or characters on a strip adjacent the periphery thereof. The carriage 24, in such case, may comprise two discs 26 and 27 adapted to hold the film disc 25 between them with the picture strip exposed beyond their peripheries as may be seen in Figs. 1 and 3. If desired, of course, the carriage discs 26 and 27, 55 or one of them, could have substantially the same diameter as the film disc 25 and be provided with peripheral openings in which to frame the pictures or characters on the film for projection, or the carriage disc could be provided with means 60 to receive and hold individual films framed in such openings. When the carriage disc is provided with openings to frame the pictures, the partition 21 may be dispensed with. Similarly, 65 the film itself may be darkened around the picture to provide a frame for the same, in which case partition 21 may be omitted. In either case the open end of the barrel would form the projection aperture.

In general the film disc 25 will have a larger 70 diameter than the barrel portion 12 and the

carriage will be mounted externally of the barrel with the periphery of the film projecting into the path of the light passing through the projection aperture. The barrel portions 12 of both sections A and B may be provided with narrow slits 28 to receive the peripheral portions of the film disc 25 and the carriage discs 26 and 27.

Referring to Fig. 2, it will be seen the trigger guard 14 on section B has been provided with a thicker projection 29 having a short shaft 30 extending forwardly therefrom upon which the carriage discs 26 and 27 are rotatably secured by a nut or collar 31. While this manner of mounting the discs has proved satisfactory, it is evident that a bracket could be provided at any 15 convenient location along the barrel to serve the same purpose as the projection 29.

Rotation may be imparted to the carriage 24 by any suitable means. In the embodiment of the invention represented in the drawing, the carriage disc 27 is provided with a ratchet wheel 32 adapted to be engaged by a pawl 33 pivoted to one end of a bell crank 34. The other end of bell crank 34 is offset as seen in Fig. 3 and extends through a slot 35 provided in the meeting edges 25 of the sections A and B to serve as a trigger 36 within the trigger guard 14. The bell crank is pivoted at 37 to the barrel portion 12 and is urged to a starting position by a spring 38 which is attached at one end to the barrel portion 12 30 and at the other end to a projection 39 on the bell crank 34. A second spring 39 is tensioned between the projection 38 and the pawl 33 to hold the latter against the ratchet wheel. It will be clear from the foregoing description that when 33 an operator presses the trigger 36, the bell crank 34 will be rotated causing the pawl 33 to engage one of the teeth of the ratchet wheel 32 and thereby rotate the carriage 24 and the film 25. The operator may advance the carriage 24 step 40 by step to project successive pictures on the film 25 or, by giving the trigger a quick pull, he may spin the carriage a number of revolutions. It is thus possible to use the projecting device of the present invention not only to project entertaining and instructive pictures but also in connection with games such as "Lotto", "Bingo", etc., to determine a number or other character by chance. The film disc 25, in such case, would carry the numbers or other characters used in 45 the game and the operator would project those which happened to stop before the aperture 20 upon a wall, ceiling or other surface for the participants to see.

It may be desirable, particularly when projecting successive pictures, to provide means for stopping the carriage 24 in proper position to frame a picture on the film 25 in the projecting aperture 20. A simple and effective means for accomplishing this result comprises a leaf spring 60 secured to the barrel portion 12 and having a ball 41 at the free end adapted to engage in regularly spaced cavities 42 on one face of the disc 27. The cavities 42 correspond in number to the pictures on the film 25 and are so arranged 65 that when the ball 41 rests in a cavity 42 the picture will be properly framed for projection. The film 25 may be placed in position in the carriage 24 either by removing disc 26, slipping the film over shaft 30 and replacing disc 26, or the 70 film 25 may have a slit extending from the center to the circumference so that it may be inserted into or withdrawn from the carriage 24 without removing disc 26. The contact friction between the faces of the discs 26 and 27 and the film 25 75

is adequate to hold the latter in position in the carriage.

A source of current for the light bulb may comprise dry cell batteries 43 and 44 positioned in the handle portion 13. As may be seen in Fig. 2, the batteries 43 and 44 are connected in series by a resilient connector 45 mounted on a stud 46 projecting up from the handle portion 13 and pressing against the respective ends of the batteries 43 and 44. When the sections A and B are made of material that conducts electricity, insulating material 47 such as rubber, paper, or the like, is interposed between the connector 45 and the holder. The other end of battery 43 is electrically connected with the center terminal 48 of the bulb 22 by means of a conductor 49 mounted in but insulated from the barrel portion 12. The ends of the conductor 49 may be in the form of spring fingers 50 and 51 to assure good electrical contact with the battery 43 and the terminal 48 respectively. The circuit from battery 44 to the outer terminal 52 of the bulb 22 may be made through the casing when it is constituted of conducting material such as metal. This circuit is normally open, however, and is closed when the operator pulls trigger 36. A satisfactory switch comprises a contact member 53 having spring ends 54 and 55. The contact member 53 is mounted in but insulated from the barrel portion 12 in such a manner that the end 54 is adapted to press against the battery terminal whereas the end 55 is in the path of some portion of the bell crank 34, for example, the shoulder 56 formed by the offset portion shown in Fig. 3. The circuit is thus closed and opened with each operative movement of the trigger, the path of the electric current being from battery 44 through contact member 53, bell crank 34, barrel portion 12, socket 23 and outer terminal 52 to the filament and then through the center terminal 48, conductor 49, battery 43 and connector 45 to the battery 43. The batteries may be held in position by stops or lugs 51. It will be apparent to those skilled in the art that the circuit may be modified in specific details and that the essential feature is a normally open circuit adapted to be closed upon operation of the trigger 36. If desired, the batteries 43 and 44 can be dispensed with and an external source of electric current be suitably connected with the conductor 49 and the contact member 53.

Although the present invention has been described in detail with respect to a preferred embodiment, it will be understood that modifications and variations may be resorted to as those skilled in the art will readily understand. Such modifications and variations are to be considered within the scope of the invention as described by the specification and defined by the appended claims.

I claim:

1. A picture projecting device comprising a gun-shaped holder having a projection aperture, a film bearing a plurality of pictures, a carriage rotatably mounted on the holder itself supporting the film with a portion thereof positioned for projection through said aperture, a movable member having operating trigger means, carriage engaging means borne by said member cooperating with said trigger means to rotate said carriage and position a different picture for projection through said aperture each time the trigger means is operated, an electric light bulb supported by the holder for illuminating the positioned picture, a source of current for said light

bulb, a normally open circuit connecting said source of current with said light bulb, switching means adapted to close the circuit when the movable member is actuated, and a projection lens in optical alignment with said picture aperture and supported by said holder whereby the image of a picture is projected when said trigger means is operated.

2. A picture projecting device in accordance with claim 1 wherein the holder is provided with means for stopping the movement of the rotatable carriage when a picture is positioned for projection through said aperture.

3. A picture projecting device comprising a gun-shaped casing having a projection aperture, an electric light bulb mounted in said casing, a film carriage rotatably mounted on said casing, said carriage being adapted itself to support a film bearing a plurality of pictures with a portion of the film framed for projection in the projection aperture, a toothed wheel drivingly connected with said carriage, trigger operated means including a bell crank pivoted to the casing and a pawl means pivoted thereon cooperating with said toothed wheel for rotating said carriage, a source of current for said bulb, a normally open circuit connecting said source of current with said bulb, and circuit closing means adapted to close the circuit when the trigger is operated, whereby operation of the trigger spins the film carriage to position another portion of the film for projection and also energizes the bulb to project the image of the picture positioned in the aperture onto a suitable surface.

4. A portable device for projecting pictures comprising a metallic holder capable of being held in a hand of the user, said holder having a projection aperture, an electric light bulb mounted within said holder with one end of the filament electrically connected to said holder, at least one dry cell within said holder, a film disc bearing a plurality of successive pictures in a strip adjacent its periphery, a carriage itself supporting said film disc rotatably mounted on said holder adapted to position successive pictures on said strip for projection through said aperture, an electrical connector between the other end of said filament and a terminal of said dry cell and insulated from said holder, switching means for electrically connecting the other terminal of said dry cell with said holder to complete the circuit through the filament of said light bulb to illuminate the latter, and means operable by a finger of the user's hand for operating said switching means and rotating said carriage and film from one picture to another whereby the picture on the film positioned in said aperture is projected from said device and a different picture is positioned for projection with each operation of said finger operated means.

5. A projecting device comprising a gun shaped casing having a barrel portion, a light bulb mounted within the barrel, a source of electric current for said light bulb, a normally open circuit connecting the source of current with the light bulb, a rotatable film carriage mounted on the casing adapted itself to support a film bearing a plurality of pictures and to position a portion of said film within the barrel intersecting the light path through the barrel in position for projection through an aperture in the end of the barrel, a trigger mounted on said casing, intermittent carriage rotating means and circuit closing means operable by said trigger, whereby operation of said trigger spins said carriage to

position a different portion of the film for projection in the aperture and illuminates the light bulb to project the image of a picture on said portion of the film through the aperture.

5 6. A picture projecting device comprising a holder adapted to be held in a hand of a user, said holder having a projection aperture, a light bulb mounted in said holder in optical alignment with said aperture, a source of current connected 10 with said light bulb through a normally open circuit, circuit closing means, picture supporting means movably mounted on said holder itself adapted to support in fixed relation thereto a plurality of pictures and bring them one at a 15 time into the beam of light flowing from said bulb through said projection aperture, means for moving said picture supporting means, and an operating member movably mounted on said holder in convenient position for operation by a 20 digit of the hand holding the device, said operating member having mechanical connection with said circuit closing means and said means for moving the picture supporting means whereby actuation of said operating means closes the circuit and moves said picture supporting means to 25 position a different picture for projection each time the operating means is actuated.

7. A picture projecting device comprising a gun-shaped holder having a projection aperture, 30 a film bearing a plurality of pictures, a carriage freely rotatably mounted on the holder itself supporting the film with a portion thereof positioned for projection through said aperture, a movable member mounted on said holder having 35 operating trigger means, carriage rotating means operatively connected with said movable member and cooperating with said trigger means to impart free rotation to said carriage and position a different portion of said film for projection 40 through said aperture each time said trigger means is actuated, an electric light bulb supported by the holder in position for illuminating

that portion of the film positioned for projection through said aperture, a normally open circuit adapted to connect said light bulb with a source of electric current, switching means for closing said circuit and illuminating said light bulb to 5 project the picture on the portion of the film positioned for projection through said aperture when said manually operable means is actuated, and an objective lens in optical alignment with 10 said picture aperture and supported by said holder whereby the image of a picture on the portion of the film positioned for projection through said aperture is projected from the device and a different picture is positioned for projection with each operation of said trigger 15 means.

8. A picture projecting device comprising a casing having a projection aperture, an electric light bulb mounted in said casing, a film carriage freely rotatably mounted on said casing, 20 said carriage being adapted itself to support a film bearing a plurality of pictures with a portion of the film positioned for projection through the projection aperture, a toothed wheel drivingly connected with said carriage, manually operable 25 means including a bell crank pivoted to the casing having means connected therewith coacting with said toothed wheel to impart free rotation to said carriage; a source of current for said bulb, a normally open circuit connecting said 30 source of current with said bulb, and circuit closing means adapted to close said circuit and illuminate the light bulb to project the picture on the portion of the film positioned for projection through the projection aperture when said 35 manually operable means is actuated whereby each operation of the manually operable means spins the film carriage to position another portion of the film for projection and projects the image of the picture on the portion of the film 40 so positioned onto a suitable surface.

CLARENCE L. STEPHENS.
